CLAIM

The ornamental design for a tent, as shown and described.

DESCRIPTION

FIG. 1 is a perspective view.

FIG. 2 is a front view.

FIG. 3 is a back view.

FIG. 4 is a right side view.

FIG. 5 is a left side view.

FIG. 6 is a top view; and,

FIG. 7 is a bottom view.

The thin dotted line portion forms no part of the claimed invention.

The thick dotted line represents a zipper for the door of the tent.
